UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT, A CORPORATION OF CONNECTICUT.

CASKET-HANDLE.

1,311,291.

Specification of Letters Patent.

Patented July 29, 1919.

Application filed April 6, 1917. Serial No. 160,273.

To all whom it may concern:

Be it known that I, EDWARD R. SARGENT, a citizen of the United States, residing in the city and county of New Haven and 5 State of Connecticut, have invented certain new and useful Improvements in Casket-Handles, of which the following is a full, clear, and exact description.

This invention relates to casket handles, 10 and more particularly to those comprising an elongated handle bar suspended by pivoted arms from one or more socket plates. The invention also has special reference to handles of this type in which the arm is 15 constructed of sheet metal.

One of the primary objects of the invention is the provision of a sheet metal arm, of improved construction, which can be very readily and economically manufactured and 20 in which provision is made for properly securing to the arm any of a number of handle bars of different dimensions, *i. e.* diameters, as may be required by conditions.

Another object of the invention is the 25 production of an arm in which a separately formed strap for holding the handle bar is located at the rear of, and secured to the arm proper; the relation of the strap to the body of the arm being such that the handle 30 bar may be securely held against lengthwise displacement. The size of the strap or clip embracing the bar may be varied within certain limits so that in making up a casket handle the arm may be used in connection 35 with any of a number of bars of different diameters.

To these, and other ends, the invention consists in the novel features and combinations of parts to be hereinafter described 40 and claimed.

In the accompanying drawing,

Figure 1, is a fragmentary front elevation of a handle embodying my improvements, showing the arm supporting the bar.

45 Fig. 2, is a side elevation of the parts shown in Fig. 1.

Fig. 3, is a rear elevation.

Fig. 4, is a side elevation of the arm alone, showing a larger strap, or clip, applied thereto.

50 Fig. 5, is a fragmentary rear elevation of the arm, proper, with the strap omitted, and

Figs. 6, and 7, are details of straps of different sizes.

55 I have not considered it necessary to illus-

trate the socket plate, or plates, and have merely shown one of the hanger arms and its means of connection with the handle bar, as it is in this means that my invention resides.

In the form shown, the arm 10 is constructed of sheet metal and made in two parts, *viz.*, the arm proper 10^a and a strap or clip, 11, for securing the handle bar 12, to the arm. The bar 12 is of general polygonal cross-section, being approximately square in the particular example shown and the strap 11 is of course shaped so as to embrace and confine the bar.

The arm proper, 10^a, is of approximately 70 U shaped cross-section, with its side edges turned inward approximately throughout its length. The side walls of the arm at the upper portion 13 thereof, are deeper than those at the lower part 14, and an angle 15 75 is formed between the inner edge of wall 14 and the lower edge of wall 13. The strap 11 is introduced between the side walls of the arm so that the upper wall of the U-shaped strap is approximately in line with 80 the upper edge of the angle 15, and it will be seen, therefore, that the rear edges of the walls 14 at opposite sides of the arm co-operate with the strap 11 in forming an approximately square socket for the bar 12. 85

The strap 11 is provided at its extremities with upwardly and downwardly projecting lugs or ears, 11^a 11^b respectively. The front wall of the arm 10^a being somewhat crowned or arched, the ears 11^a 11^b are bent to conform to the rear surface of such wall and these lugs are riveted to the wall by small rivets 16. The rounded heads of the rivets are preferably located at the front surface of the arm, and the rivet shanks are upset 90 or clenched at the rear of the arm.

It will be noted that the hanger arm proper is not only turned in at the sides thereof, but also at the bottom, as shown at 17. In other words the arm has a turned-in 100 wall extending continuously along one side, across the bottom, and along the other side, and preferably the in-turned wall 17, at the bottom, will be curved as shown in Figs. 1 and 3. By shaping the arm in the manner 105 described, the same is not only made very shapely, but also very strong and rigid, in spite of the fact that it is constructed of comparatively light sheet metal. The lower part of the arm extends somewhat below the 110

lower surface of the bar. The bar may be very securely held in place in the arm by means of a screw (not shown) engaging a threaded hole 18 in the rear wall of the strap (Fig. 3) or by a staple 19 passing through the rear wall of the strap and between the rear wall of the strap and the opposing lower face of the square bar. This staple is driven in to bind the parts together frictionally, and as it is driven in it exerts a forward thrust on the bar which causes it to be tightly forced against the inner edges of the in-turned walls 14 of the arm. Thus these edges are usually caused to bite into the bar to a certain extent, thereby aiding in preventing longitudinal displacement of the bar.

It will be observed that the legs of the clip or strap extend into the space between the rearwardly turned side walls of the arm member and across this space to the rear surface of the arm member, where said legs are provided with lugs lying flatwise against the rear surface of the arm member and riveted thereto. It will also be noted that the upper leg of the clip confines the bar over a certain area located between the side walls of the arm member.

By the construction of the arm and strap, as herein described, bars of different cross-sectional dimensions may be used in connection with the same arm. In Fig. 4, I have shown a strap 11^c used in connection with the arm 10, which strap 11^c is larger than the strap 11, to accommodate a larger handle bar. The upper wall of the strap 11^c is positioned in the same location as the upper wall of strap 11, as previously described, but the rear wall of the strap 11^c is farther back and the bottom wall is lower down. In this case therefore the inner edge of wall 14 and the lower edge of wall 13 complete a larger square adapted to accommodate a larger bar than the bar 12. However while these straps are of different sizes, I prefer to make them interchangeable by so forming and perforating the ears that the fastening rivets will in every case pass through the same pair of rivet holes 20 in the front wall of the arm.

The improved casket handle may be made very conveniently in suitable dies, and as the straps are formed separately from the arms and are located entirely at the rear of the arms, where they are substantially invisible, said straps may be made of metal of inferior quality to that used in the arms proper, without detracting from the strength or salability of the article. The fact that bars of different diameters may be used with the same size of arm, as required by different conditions, is also a feature of considerable importance.

The top, bottom, and rear walls of the strap are preferably made of such width

that they fit in snugly between the side walls of the arm proper, as this increases the strength and rigidity of the construction. The side walls of the arm prevent lateral movement of the strap with the use of only two small fastening rivets.

Without limiting myself to the precise construction shown, I claim:

1. In a casket handle or the like, a sheet metal arm member having rearwardly turned side walls extending lengthwise of said arm, a bar extending transversely across said arm member at the rear thereof in engagement with the edges of said rearwardly turned side walls, a separate bar-supporting clip of substantially U-shape set in between the side walls of said arm member at opposite sides of said bar, the legs of said clip extending to the rear surface of the arm member between said side walls and being provided at their ends with outwardly bent lugs lying flatwise against the rear surface of the arm member on opposite sides of the bar, and fastening members for securing said lugs to the arm member. 90

2. In a casket handle or the like, a sheet metal arm member having rearwardly turned side walls, said side walls being cut away at the lower portion of the arm member to form a bar receiving recess, a bar in said recess at least partially overhung by the side walls of said arm member above said recess, a separate clip of substantially U-shape embracing said bar at the rear of said arm member and having legs set in between said side walls, the upper leg of said clip extending between the side walls overhanging the bar at the top into engagement with the rear surface of the arm member and having an upwardly bent lug 100 lying flatwise against said rear surface, the lower leg of said clip extending into engagement with the rear surface of said arm member below the bar and having a downwardly turned lug lying flatwise against 105 said surface, and fastening means for securing said lugs to the rear surface of the arm member. 110

3. In a casket handle, a sheet metal hanger member which is of U-shaped cross-section throughout the greater part of its length, a handle bar traversing said hanger member at the rear thereof in proximity to the inner edges of the turned-in side walls of said hanger member, and a clip for holding 120 the bar in place set in snugly between the side walls of said hanger member and having upper and lower securing lugs fastened to the front wall of the hanger member. 115

4. In a casket handle, a sheet metal arm member which is of U-shaped cross-section throughout the greater part of its length, having turned-in side walls and a turned-in bottom wall, a bar extending across the inner edges of said side walls, and a bar 125 130

holding clip set in snugly between the side walls of said arm member and fastened to the front wall thereof.

5. In a casket handle, a sheet metal arm member which is of U-shaped cross-section throughout the greater part of its length, having turned-in side walls and a turned-in bottom wall, a bar holding clip set in snugly between the side walls of said arm member and fastened to the front wall thereof, said side walls being partially cut away at the lower portion of said arm member to form a recess, and a bar held in said recess by said clip.
- 10 6. In a casket handle, or the like, a sheet

metal handle of substantially U-shape in cross-section having rearwardly turned parallel sides, said sides partly cut away to form shoulders, a handle bar extending across said handle in engagement with said sides 20 and shoulders, a clip constructed to straddle said bar to secure the same in place, lugs upon the respective ends of said clip curved to conform to the curved inner face of said handle, and means for firmly securing said 25 curved lugs to the inner face of said handle.

In witness whereof I have hereunto set my hand on the 5th day of April, 1917.

EDWARD R. SARGENT.
